UNITED STATES PATENT OFFICE

108,143

DESIGN FOR A WRENCH MEMBER

Sigmund Mandl, Milwaukee, Wis., assignor to
Blackhawk Mfg. Co., Milwaukee, Wis., a cor-
poration of Wisconsin

Application February 27, 1937, Serial No. 67,905

Term of patent 7 years

To all whom it may concern:

Be it known that I, Sigmund Mandl, a citizen of the United States and a resident of Milwaukee, in the county of Milwaukee and State of Wisconsin, have invented a new, original, and ornamental Design for a Wrench Member, of which the following is a specification, reference being had to the accompanying drawing forming a part thereof.

Figure 1 is an elevational view of a wrench member showing my new design.

Figure 2 is a sectional view of the member shown in Figure 1.

The characteristic features of my design reside

in a wrench member having a cylindrical body portion and a reduced cylindrical neck portion merging therewith, substantially as shown, the free end of the body portion being rounded and said body portion having a series of relatively deep under-cut grooves positioned adjacent the neck portion and spaced therefrom a distance substantially equal to the width of said series of grooves.

I claim:

The ornamental design for a wrench member, as shown and described.

SIGMUND MANDL.
